(57) **CLAIM**

We are claiming the ornamental design for a portable appliance cord wrap, as shown and described.

DESCRIPTION

FIG. 1 is a front perspective view of a portable appliance cord wrap showing our new design in one possible environment;

FIG. 2 is an enlarged, perspective view of the portable appliance cord wrap thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The portion shown in broken lines is for illustration purposes only and forms no part of the claimed design.
